(57) **ABSTRACT**

A color photographic silver halide material having a support and at least one photosensitive silver halide emulsion layer which is associated with a cyan coupler of the formula (I):

in which

R_1 , R_2 , R_3 , Z_1 , Y_1 and n have the meaning stated in the description,

is distinguished by elevated dye stability of the dye produced from the coupler by chromogenic processing.

12 Claims, No Drawings

1

COLOR PHOTOGRAPHIC SILVER HALIDE
MATERIAL

This invention relates to a color photographic silver halide material having a novel cyan coupler.

It is known from JP-N 59 111 645, U.S. Pat. No. 5,008,180 and U.S. Pat. No. 5,686,235 to use 2,5-diacylaminophenols having a sulfonyl group as cyan couplers. However, the color reproduction and dye stability of the dyes produced from the couplers by chromogenic processing do not meet requirements.

The object of the invention was to provide cyan couplers which are improved with regard to these properties. This object is achieved with the couplers described below.

The present invention accordingly provides a color photographic silver halide material having a support and at least one photosensitive silver halide emulsion layer which is associated with a cyan coupler of the formula (I):

in which

R₁, R₂ mean H, alkyl, alkenyl, aryl or hetaryl,

R₃ means alkyl, alkenyl, aryl or hetaryl,

Z₁ means H or a group eliminable under the conditions of chromogenic development,

Y₁ means —COR₄, —CO₂R₄, —CONR₄R₅, —SO₂R₄, —SO₂NR₄R₅, —CO—CO₂R₄, —COCONR₄R₅ or a group of the formula

R₄ means alkyl, alkenyl, aryl or hetaryl,

R₅ means H or R₄,

R₆ means —N= or —C(R₉)=

R₇, R₈, R₉ mean —OR₅, —SR₅, —NR₄R₅, —R₅ or Cl and

n means 1 or 2.

Within the formula, the following groups of couplers are preferred:

(1) couplers in which n means 1 and R₁ to R₉, Z₁ and Y₁ have the stated meaning.

(2) couplers in which n means 2, Y₁ means —CO—Y₁₁ and Y₁₁ means alkenyl or hetaryl and R₁ to R₅ and Z₁ have the stated meaning.

2

(3) couplers in which n means 2, Y₁ means —SO₂R₁₀, —SO₂N(R₁₀)₂, —CO₂R₁₀, —COCO₂—R₁₀ or —COCO—N(R₁₀)₂ and R₁₀ means alkyl, aryl, alkenyl or hetaryl and

R₁ to R₃ and Z₁ have the stated meaning.

(4) couplers in which n means 2, Y₁ means a residue of the formula

and R₁ to R₃, R₆ to R₈ and Z₁ have the stated meaning.

(5) couplers in which n means 2, Y₁ means a residue of the formula

wherein

R₁₀ means H, Cl, CN, Br, F, alkylcarbonyl, arylcarbonyl, alkylaminocarbonyl, arylaminocarbonyl, alkoxy carbonyl or aryloxycarbonyl and R₁ to R₃ and Z₁ have the stated meaning.

In the formula (I) and the compounds (1) to (4), the substituents have the following preferred meaning:

R₁, R₂H, alkyl, aryl,

R₃ alkyl, aryl,

Z₁ H, Cl, alkoxy, aryloxy, alkylthio, arylthio,

R₆ —N=,

R₇, R₈—OR₅, —NR₄R₅, —Cl.

Very particularly preferably,

R₂ means H and

R₄ means alkyl or aryl.

Alkyl and alkenyl residues may be linear, branched or cyclic and in turn be substituted.

Aryl and hetaryl residues may in turn be substituted, wherein aryl is in particular phenyl.

Possible substituents for the alkyl, alkenyl, aryl or hetaryl

residues are: alkyl, alkenyl, aryl, hetaryl, alkoxy, aryloxy, alkenyloxy, hydroxy, alkylthio, arylthio, halogen, cyano, acyl, acyloxy, acylamino, wherein an acyl residue may be derived from an aliphatic, olefinic or aromatic carbonic, carboxylic, carbamic, sulfonic, sulfonamido, sulfinic, phosphoric, phosphonic or phosphorous acid.

19

The compounds according to the invention are produced in an analogous manner to the method stated in U.S. Pat. No. 5,686,235.

The compounds of the formula (I) are preferably used in a quantity of 5 to 2000 mg/m², in particular of 10 to 1000 mg/m² and very particularly preferably in a quantity of 20 to 500 mg/m² of the material.

Examples of color photographic materials are color negative films, color reversal films, color positive films, color photographic paper, color reversal photographic paper, color-sensitive materials for the dye diffusion transfer process or the silver dye bleaching process. A review may be found in Research Disclosure 37038 (1995) and Research Disclosure 38957 (1996).

The photographic materials consist of a support, onto which at least one photosensitive silver halide emulsion layer is applied. Suitable supports are in particular thin films and sheets. A review of support materials and auxiliary layers applied to the front and reverse sides thereof is given in Research Disclosure 37254, part 1 (1995), page 285 and in Research Disclosure 38957, part XV (1996), page 627.

The color photographic materials conventionally contain at least one red-sensitive, one green-sensitive and one blue-sensitive silver halide emulsion layer, optionally together with interlayers and protective layers.

Depending upon the type of photographic material, these layers may be differently arranged. This is demonstrated for the most important products:

Colour photographic films such as color negative films and color reversal films have on the support, in the stated sequence, 2 or 3 red-sensitive, cyan-coupling silver halide emulsion layers, 2 or 3 green-sensitive, magenta-coupling silver halide emulsion layers and 2 or 3 blue-sensitive, yellow-coupling silver halide emulsion layers. The layers of identical spectral sensitivity differ with regard to their photographic sensitivity, wherein the less sensitive sublayers are generally arranged closer to the support than the more highly sensitive sublayers.

A yellow filter layer is conventionally located between the green-sensitive and blue-sensitive layers which prevents blue light from penetrating into the underlying layers.

Possible options for different layer arrangements and the effects thereof on photographic properties are described in J. Inf. Rec. Mats., 1994, volume 22, pages 183–193 and in Research Disclosure 38957, part XI (1996), page 624.

Colour photographic paper, which is usually substantially less photosensitive than a color photographic film, conventionally has on the support, in the stated sequence, one blue-sensitive, yellow-coupling silver halide emulsion layer, one green-sensitive, magenta-coupling silver halide emulsion layer and one red-sensitive, cyan-coupling silver halide emulsion layer; the yellow filter layer may be omitted.

The number and arrangement of the photosensitive layers may be varied in order to achieve specific results. For example, all high sensitivity layers may be grouped together in one package of layers and all low sensitivity layers may be grouped together in another package of layers in order to increase sensitivity (DE 25 30 645).

The substantial constituents of the photographic emulsion layers are binder, silver halide grains and color couplers.

Details of suitable binders may be found in Research Disclosure 37254, part 2 (1995), page 286 and in Research Disclosure 38957, part II.A (1996), page 598.

Details of suitable silver halide emulsions, the production, ripening, stabilisation and spectral sensitisation thereof,

20

including suitable spectral sensitisers, may be found in Research Disclosure 37254, part 3 (1995), page 286, in Research Disclosure 37038, part XV (1995), page 89 and in Research Disclosure 38957, part V.A (1996), page 603.

Photographic materials with camera sensitivity conventionally contain silver bromide-iodide emulsions, which may optionally contain small proportions of silver chloride. Photographic print materials contain either silver chloride-bromide emulsions containing up to 80 wt. % of AgBr or silver chloride-bromide emulsions containing above 95 mol % of AgCl.

Details of color couplers maybe found in Research Disclosure 37254, part 4 (1995), page 288, in Research Disclosure 37038, part II (1995), page 80 and in Research Disclosure 38957, part X.B (1996), page 616. The maximum absorption of the dyes formed from the couplers and the developer oxidation product is preferably within the following ranges: yellow coupler 430 to 460 nm, magenta coupler 540 to 560 nm, cyan coupler 630 to 700 nm.

In order to improve sensitivity, grain, sharpness and color separation in color photographic films, compounds are frequently used which, on reaction with the developer oxidation product, release photographically active compounds, for example DIR couplers which eliminate a development inhibitor.

Details relating to such compounds, in particular couplers, may be found in Research Disclosure 37254, part 5 (1995), page 290, in Research Disclosure 37038, part XIV (1995), page 86 and in Research Disclosure 38957, part X.C (1996), page 618.

Colour couplers, which are usually hydrophobic, as well as other hydrophobic constituents of the layers, are conventionally dissolved or dispersed in high-boiling organic solvents. These solutions or dispersions are then emulsified into an aqueous binder solution (conventionally a gelatine solution) and, once the layers have dried, are present as fine droplets (0.05 to 0.8 µm in diameter) in the layers.

Suitable high-boiling organic solvents, methods for the introduction thereof into the layers of a photographic material and further methods for introducing chemical compounds into photographic layers may be found in Research Disclosure 37254, part 6 (1995), page 292.

The non-photosensitive interlayers generally arranged between layers of different spectral sensitivity may contain agents which prevent an undesirable diffusion of developer oxidation products from one photosensitive layer into another photosensitive layer with a different spectral sensitisation.

Suitable compounds (white couplers, scavengers or DOP scavengers) may be found in Research Disclosure 37254, part 7 (1995), page 292, in Research Disclosure 37038, part III (1995), page 84 and in Research Disclosure 38957, part X.D (1996), pages 621 et seq.

The photographic material may also contain UV light absorbing compounds, optical brighteners, spacers, filter dyes, formalin scavengers, light stabilisers, antioxidants,

D_{min} dyes, plasticisers (latices), biocides and additives to improve coupler and dye stability, to reduce color fogging and to reduce yellowing, and others. Suitable compounds may be found in Research Disclosure 37254, part 8 (1995), page 292, in Research Disclosure 37038, parts IV, V, VI, VII, X, XI and XIII (1995), pages 84 et seq. and in Research Disclosure 38957, parts VI, VIII, IX and X (1996), pages 607 and 610 et seq.

The layers of color photographic materials are conventionally hardened, i.e. the binder used, preferably gelatine, is crosslinked by appropriate chemical methods.

Suitable hardener substances may be found in Research Disclosure 37254, part 9 (1995), page 294, in Research Disclosure 37038, part XII (1995), page 86 and in Research Disclosure 38957, part II.B (1996), page 599.

Once exposed with an image, color photographic materials are processed using different processes depending upon their nature. Details relating to processing methods and the necessary chemicals are disclosed in Research Disclosure 37254, part 10 (1995), page 294, in Research Disclosure 37038, parts XVI to XXIII (1995), pages 95 et seq. and in Research Disclosure 38957, parts XVIII, XIX and XX (1996), pages 630 et seq. together with example materials.

The magenta couplers preferably comprise those having pyrazolotriazole structures of the formulae (II) or (III)

EXAMPLES**Example 1**

30 A color photographic recording material suitable for rapid processing was produced by applying the following layers onto a layer support of paper coated on both sides with polyethylene. Quantities are stated in each case per 1 m². The silver halide application rate is stated as the corresponding quantities of AgNO₃.

35

Layer structure 101Layer 1: (Substrate layer)

40 0.10 g of gelatine
Layer 2: (Blue-sensitive layer)

Blue-sensitive silver halide emulsion (99.5 mol % chloride, 0.5 mol % bromide, average grain diameter 0.75 µm) prepared from 0.4 g of AgNO₃, spectrally sensitised with 0.6 mg of compound BS-1

45 1.25 g of gelatine
0.30 g of yellow coupler GB-1
0.15 g of yellow coupler GB-2
0.30 g of tricresyl phosphate (TCP)
0.10 g of isoctadecanol
0.05 g of stabiliser ST-1
50 0.10 g of stabiliser ST-2
Layer 3: (Interlayer)

0.10 g of gelatine
0.08 g of DOP scavenger S-4
0.04 g of DOP scavenger SC-1
0.01 g of DOP scavenger SC-2
55 0.12 g of TCP
Layer 4: (Green-sensitive layer)

Green-sensitive silver halide emulsion (99.5 mol % chloride, 0.5 mol % bromide, average grain diameter 0.45 µm) prepared from 0.2 g of AgNO₃, spectrally sensitised with 0.12 mg of compound GS-1

60 1.10 g of gelatine
0.10 g of magenta coupler M-7
0.10 g of magenta coupler M-4
0.15 g of stabiliser ST-3
0.20 g of stabiliser ST-4
0.20 g of TCP
65 0.20 g of isotetradecanol
0.20 g of tris(2-ethylhexyl) phosphate

-continued

Layer structure 101

Layer 5: (UV protective layer)

1.05 g of gelatine
 0.20 g of UV absorber UV-1
 0.10 g of UV absorber UV-2
 0.05 g of UV absorber UV-3
 0.08 g of DOP scavenger S-4
 0.04 g of DOP scavenger SC-1
 0.01 g of DOP scavenger SC-2
 0.15 g of TCP
 0.15 g of tris(2-ethylhexyl) phosphate

Layer 6: (Red-sensitive layer)

Red-sensitive silver halide emulsion (99.5 mol % chloride, 0.5 mol % bromide, average grain diameter 0.48 μm) prepared from 0.28 g of AgNO_3 , spectrally sensitised with 0.04 mg of compound RS-1 and stabilised with 0.56 mg of stabiliser ST-5

1.00 g of gelatine
 0.10 g of cyan coupler C-1
 0.30 g of cyan coupler C-2
 0.20 g of dibutyl phthalate (DBP)
 0.20 g of TCP
 0.10 g of stabiliser ST-6

Layer 7: (UV protective layer)

1.05 g of gelatine
 0.10 g of UV absorber UV-1
 0.30 g of UV absorber UV-2
 0.05 g of UV absorber UV-3
 0.20 g of tris(2-ethylhexyl) phosphate

Layer 8: (Protective layer)

0.90 g of gelatine
 0.05 g of optical brightener W-1
 0.07 g of polyvinylpyrrolidone
 1.20 mg of silicone oil
 2.50 mg of polymethyl methacrylate spacers, average particle size 0.8 μm
 0.30 g of instant hardener H-1

The following compounds are used in Example 1:

40

45

W-1

Processing:

Samples of the material are exposed under a grey wedge through a red filter and processed as follows:

a)	Colour developer - 45 s - 35° C.	
	Triethanolamine	9.0 g
	N,N-Diethylhydroxylamine	2.0 g
	Bis(2-sulfoethyl)hydroxylamine disodium salt	2.0 g
	Diethylene glycol	0.05 g
	3-Methyl-4-amino-N-ethyl-N-methane-sulfonamidoethylaniline sulfate	5.0 g
	Potassium sulfite	0.2 g
	Triethylene glycol	0.05 g
	Potassium carbonate	22 g
	Potassium hydroxide	0.4 g
	Ethylenediaminetetraacetic acid, disodium salt	2.2 g
	Potassium chloride	2.5 g
	1,2-Dihydroxybenzene-3,4,6-trisulfonic acid trisodium salt	0.3 g
	make up with water to 1000 ml; pH 10.0	
b)	Bleach/fixing bath - 45 s - 35° C.	
	Ammonium thiosulfate	75 g
	Sodium hydrogen sulfite	13.5 g
	Ammonium acetate	2.0 g
	Ethylenediaminetetraacetic acid (iron/ammonium salt)	57 g
	Ammonia, 25%	9.5 g
	make up with acetic acid to 1000 ml; pH 5.5	
c)	Rinsing - 2 min - 33° C.	
d)	Drying	

The percentage yellow and magenta secondary densities were then determined at cyan density $D_{cyan}=1.0$ (SD_{yellow} , $SD_{magenta}$). The results are shown in Table 1. The samples are also stored in darkness for 42 days at 85° C. and 60% relative humidity and the percentage reductions in density at maximum density (ΔD_{max}) were determined. Further samples are exposed to $15 \cdot 10^6$ lux·h of light from a daylight-standardised xenon lamp at 35° C. and 85% relative humidity. The reduction in density at $D=0.6$ is then determined [$\Delta D_{0.6}$].

The following oil formers are also used in the other samples:

TABLE 1

Layer structure	Layer 6		Secondary density (%)		Dark stability	Light stability (%)
	Cyan coupler	Oil former	SD _{yellow}	SD _{magenta}	ΔD _{max} (%)	ΔD _{1.0} (%)
101(C)	C-1/C-2 (1:3)	DBP/TCP (1:1)	11.8	28.3	-37	-27

TABLE 1-continued

(C: comparison; I: according to the invention)

5	Layer structure	Layer 6		Secondary density (%)		Dark stability	Light stability (%)
		Cyan coupler	Oil former	SD _{yellow}	SD _{magenta}	ΔD _{max} (%)	ΔD _{1.0} (%)
10	102(C)	CA (1:3)	DBP/OF-1 (1:1)	12.7	37.9	-4	-36
	103(C)	C-13 (1:3)	TCP/OF-2 (1:1)	9.9	27.8	-13	-78
15	104(C)	C-17 (1:1)	DBP/OF-1 (1:1)	9.6	31.4	-7	-31

25							

In comparison with conventional phenolic cyan couplers (C-1 and C-2), conventional diacylaminophenol cyan couplers (C-4), heterocyclic cyan couplers (C-13) and the special diacylaminophenol cyan couplers according to U.S. Pat. No. 5,686,235 (C-17), only the couplers according to the invention yield dyes which are simultaneously distinguished by good light stability, outstanding dark stability and good color reproduction.

What is claimed is:

35 1. A color photographic silver halide material which comprises a support and at least one photosensitive silver halide emulsion layer which is associated with a cyan coupler of the formula (I):

in which

R₁ and R₂ independently mean H, alkyl, alkenyl, aryl or hetaryl,

R₃ means alkyl, alkenyl, aryl or hetaryl,

Z₁ means H or a group eliminable under the conditions of chromogenic development,

Y₁ means COY₁₁, —CO₂R₄, —CONR₄R₅, —SO₂R₄, —SO₂NR₄R₅, —CO—CO₂R₄, —COCONR₄R₅ or a group of the formula

Y₁₁ means alkenyl or hetaryl,

R₄ means alkyl, alkenyl, aryl or hetaryl,

R₅ means H or R₄,

R₆ means —N= or —C(R₉)=

35

R_7 , R_8 and R_9 independently mean $-\text{OR}_5$, $-\text{SR}_5$, $-\text{NR}_4\text{R}_5$, $-\text{R}_5$ or Cl and

n means 1 or 2 with the proviso that n means 2 when Y_1 means COY_{11} .

2. The color photographic silver halide material according to claim 1, wherein n means 1.

3. The color photographic silver halide material according to claim 1 wherein,

n means 2,

Y_1 means $-\text{SO}_2\text{R}_{10}$, $-\text{SO}_2\text{N}(\text{R}_{10})_2$, $-\text{CO}_2\text{R}_{10}$, $-\text{COCO}_2\text{R}_{10}$ or $-\text{COCON}(\text{R}_{10})_2$ and

R_{10} means alkyl, aryl, alkenyl or hetaryl.

4. The color photographic material according to claim 1, wherein

n means 2 and

5. The color photographic material according to claim 1, wherein

n means 2 and

Y_1 means a residue of the formula

wherein

R_{10} means H, Cl, CN, Br, F, alkylcarbonyl, arylcarbonyl, alkylaminocarbonyl, arylaminocarbonyl, alkoxy carbonyl or aryloxycarbonyl.

6. The color photographic material according to claim 1, wherein

R_1 and R_2 independently mean H, alkyl or aryl,

R_3 means alkyl or aryl,

Z_1 means H, Cl, alkoxy, aryloxy, alkylthio or arylthio,

R_6 means $-\text{N}=$

R_7 and R_8 independently mean $-\text{OR}_5$, $-\text{NR}_4\text{R}_5$ or Cl.

7. The color photographic material according to claim 1, wherein the compounds of the formula (I) are used in a quantity of 5 to 2000 mg/m².

8. The color photographic material according to claim 1, wherein the material contains a magenta coupler of the formulae (II) or (III):

36

-continued

(III)

in which

X_{21} means H or a group eliminable under the conditions of chromogenic development,

R_{21} means optionally substituted alkyl,

R_{22} means R_{21} or aryl,

wherein the sum of all the C atoms of the residues R_{21} and R_{22} in one coupler molecule is at least 12.

9. The color photographic silver halide material according to claim 1, wherein the material contains a DOP scavenger of the formula (IV):

in which

R_{41} mutually independently means alkyl, cycloalkyl, aryl, halogen, SR_{45} , $\text{NR}_{46}\text{R}_{47}$, nitro, cyano, SO_2R_{48} , COOR_{49} , COR_{50} , hetaryl or hydrogen,

R_{42} has the same meaning as R_{41} or means $-\text{OR}_{52}$,

R_{43} and R_{44} mutually independently mean $-\text{OR}_{51}$ or have the meaning of R_{41} ,

R_{45} and R_{49} mutually independently mean alkyl, cycloalkyl, alkenyl, aryl or hetaryl,

R_{46} and R_{47} mutually independently mean H, R_{44} , COR_{50} , COOR_{49} or $-\text{SO}_2\text{R}_{48}$,

R_{48} and R_{50} mutually independently mean alkyl, cycloalkyl, alkenyl, aryl, hetaryl or $\text{NR}_{40}\text{R}_{47}$,

R_{51} means hydrogen, alkyl or aryl,

R_{52} means hydrogen, alkyl, aryl, alkylcarbonyl, alkenylcarbonyl, arylcarbonyl, alkoxy carbonyl, alkenyloxy carbonyl, carbamoyl, alkylsulfonyl or arylsulfonyl,

o means 0, 1, 2, 3 or 4 and

p means 0, 1, 2, or 3,

wherein two residues R_{43} or R_{44} may in each case mean a fused carbocyclic or heterocyclic ring or the compound of the formula (IV) is attached to a polymer chain via a residue R_{43} or R_{44} .

10. The color photographic material according to claim 2, wherein R_2 is H and R_4 alkyl or aryl.

11. The color photographic material according to claim 1, wherein the compounds of the formula 1 are used in a quantity of 10 to 1000 mg/m².

12. The color photographic material according to claim 1, wherein the compounds of the formula 1 are used in a quantity of 20 to 500 mg/m².
